TRACTION DEVICE FOR AUTOMOBILES

Ralph Hodgkinson, Worcester, Mass.

Application June 8, 1936, Serial No. 84,046

20 Claims. (Cl. 301—47)

This invention relates to devices for increasing the traction of automobiles. It is customary to use detachable cross chains or so-called "mud hooks" for such purposes, but the application and removal of such devices is laborious and otherwise objectionable.

It is the general object of my invention to provide an improved device for increasing traction, which device is to be permanently installed in an automobile and which may be rendered operative or inoperative as desired.

A further object of my invention is to provide means for positioning all parts of the device clear of the ground when the device is inoperative.

My invention further relates to arrangements and combinations of parts which will be herein-after described and more particularly pointed out in the appended claims.

Preferred forms of the invention are shown in the drawings, in which

Fig. 1 is a front elevation, partly in section, of one form of my improved traction device;

Fig. 2 is a side elevation thereof, partly in section;

Fig. 3 is a detail sectional view, taken along the line 3—3 in Fig. 2;

Fig. 4 is an enlarged detail view of a plunger element;

Fig. 5 is a side elevation of a cam plate forming part of my invention;

Fig. 6 is a plan view, looking in the direction of the arrow 6 in Fig. 5;

Figs. 7 and 8 are detail plan views, partly in section and illustrating the operation of my invention;

Fig. 9 is a side elevation of a plunger carrier;

Fig. 10 is a sectional plan view, taken along the line 10—10 in Fig. 9;

Fig. 11 is a partial front elevation showing a modified construction;

Fig. 12 is a side view thereof, looking in the direction of the arrow 12 in Fig. 11 and showing certain parts in section; and

Fig. 13 is a plan view, looking in the direction of the arrow 13 in Fig. 11.

Referring to the drawings, I have shown a wheel 15 mounted on a housing 16 and secured to a driving shaft 17, all substantially of the usual construction. The wheel is provided with a brake drum 18 and supports the usual tire 19.

My improved traction device comprises a casing 20 (Figs. 1 and 2) having a flange 21 forming a supporting bearing for the casing on the outside of the housing 16. A removable cover

plate 22 surrounds the housing 16 and completes the casing.

A plurality of trunnion blocks 25 are pivotally mounted between the casing 20 and the cover plate 22 and provide swivel bearings for sleeves 27 which are arranged for angular movement therein. Each sleeve 27 is provided with a cam-engaging arm 30 at its inner end and with a friction arm 31 at its outer end and is also provided with a shoulder 32 which limits inward sliding movement of the sleeve relative to its trunnion block 25.

A coil spring 33 surrounds each sleeve 27 and has one end fixed in the casing 20 and the other end engaging the arm 30, as clearly shown in Fig. 1. The spring 33 tends to turn the sleeve in a direction to force the friction arm 31 against the adjacent surface of the tire 19, and the spring 33 also acts to seat the shoulder 32 firmly against the associated trunnion block 25.

The cam-engaging arm 30 is normally seated in a recess 35 (Fig. 8) in one of the cam projections 36 on a cam plate 37. The cam plate 37 is slidable axially on the housing 16 but is held from rotation by a key 38 (Fig. 1) loosely fitting a keyway 39 in the cam plate 37.

A forked lever 40 is pivotally mounted on a stud 41 extending through ears 42 on the housing 16 and the lower forked ends of the lever extend through a central opening 43 in the cover plate 22 and engage the outer face of the cam plate 37.

A coil spring 45 (Figs. 7 and 8) is mounted on the housing 16 and presses outward against the cam plate 37, tending to move the plate from its holding position, shown in Fig. 8, to its released position, as shown in Fig. 7.

The plunger carrier 50 (Figs. 9 and 10) is provided with a bearing portion 51 adapted to be mounted on the outer face of the flange 21 of the casing 20, and is provided with three arms 52 adapted to support studs 53 extending between the side walls of the carrier. One of the arms is extended outward and provided with an offset lug or projection 55 to engage a stop screw 56 (Fig. 1) adjustably mounted in the casing 20.

A plunger 60 is slidable longitudinally in each sleeve 27 and is slotted at its outer end (as indicated at 61 in Fig. 2 and more clearly in the modified construction of Fig. 12) to receive a traction plate 64 which may be secured in the plunger 60 by screws 66.

Each traction plate 64 extends over and partially embraces the tire 19 and is provided with a roughened tread portion 67. When in normal

inoperative position, the traction plates 64 clear the tire 19 and are not engaged thereby.

The lower end of each plunger 60 is preferably square in cross section and is provided with an elongated slot 70 having a bearing block 71 slideable therein and forced yieldingly toward the inner end of the plunger by a coil spring 72.

Each bearing block 71 may be provided with ribs 73 slideable in longitudinal grooves in the side walls of the slots 70 or may be otherwise held from displacement. Each block 71 cooperates with the adjacent end of the associated plunger 60 to form a bearing for one of the cross pins 53 in the plunger carrier 50 previously identified.

Having described one form of my invention, the method of operation and advantages thereof are as follows:

Under normal running conditions a link 75 (Fig. 2) is manually adjusted outward in the direction of the arrow *a*, thus forcing the lower ends of the forked lever 40 inward against the cam plate 37 and moving the cam plate from the position shown in Fig. 7 to that shown in Fig. 8, in which position the cam-engaging arms 30 on the sleeves 27 will be seated in the recesses 35 of the cam projections 36 on the cam plate 37.

The friction arms 31 will thus be held clear of the tire 19. The cam recesses are so located angularly that the traction plates 64 will be positioned as indicated in Figs. 1 and 2, well out of possible contact with the ground.

The link 75 may be connected to any kind of a shipper handle 76 or other holding device adapted to hold the parts normally in the position above described.

If the automobile approaches bad traveling occasioned by snow, mud, or sand, the holding device 76 for the link 75 may be released, thus allowing the spring 45 to move the cam plate 37 out of engagement with the cam-engaging arms 30 on the sleeves 27. The springs 33 then act to swing the friction arms 31 against the tire 19, and the casing 20 and all associated parts will thereafter rotate with the tire and wheel.

As soon as one of the traction plates engages the ground, it will be forced inward and will exert pressure through its spring 72 and bearing 71 on the plunger carrier 50, moving the carrier angularly in a direction to draw the two other traction plates 64 inward against the tire.

As each plate 64 engages the ground, it repeats the tightening action of the carrier 50, so that the engagement of the traction plates with the tire is substantially continuous.

The traction device will continue to operate as described until the shipper handle or control device 76 is again manually operated to move the link 70 in the direction of the arrow *a* in Fig. 2, thus forcing the cam plate 37 inward. When this is done, the cam-engaging arms 30 will be again caught in the recesses 35 of the cam portions 36, and the device will again become inoperative with the traction plates angularly positioned as shown in Fig. 1.

It will be apparent that the operator has the traction device at all times under his immediate control, and that he can throw the device into and out of operation without leaving his driving position or stopping the motion of the car.

A modified construction is shown in Figs. 11 to 13 in which no part corresponding to the sleeve 27 is used. The plungers 80 are slideable longitudinally in trunnion boxes 81 which may be supported between a casing 20 and cover plate 22 as previously described.

The upper end of each plunger is slotted at 82 to receive a traction plate 83, and a friction arm 84 is clamped or otherwise removably secured to the upper end of the plunger. A cam-engaging arm 85 is similarly secured to an intermediate 5 portion of each plunger.

The lower end of each plunger is reduced in size as indicated at 86 and is slideable in a trunnion block 87.

The coil spring 88 is mounted on the reduced 10 portion 86 and acts to force the plunger longitudinally in the bearing 87 and to cause a nut 89 to engage the lower face of the associated trunnion block 87.

Each spring 88 also acts to turn its plunger 80 15 anti-clockwise, as indicated by the arrow *b* in Fig. 13, which movement will cause the friction arm 84 on each plunger to engage the adjacent tire.

The trunnion bearings 87 are mounted in bearing openings in a carrier 90, corresponding in 20 function to the carrier 50 previously described. This modified construction involves the use of two trunnion bearing blocks for each plunger but is otherwise somewhat more simple than the construction first described. The use and advantages 25 of the modified construction is the same as in the first form.

Having thus described my invention and the advantages thereof, I do not wish to be limited to the details herein disclosed, otherwise than 30 as set forth in the claims, but what I claim is:—

1. A traction increasing device for an automobile having a wheel and tire comprising a casing loosely mounted for rotation concentric with the wheel axis, a plurality of spaced outwardly extending plungers mounted in said casing and having traction plates at their outer ends overlying the tire on said wheel, a friction arm for each plunger movable angularly about the axis of said plunger to engage the tire, a second arm 40 connected to each friction arm, a device movable to a position to engage said second arms and to move said friction arms out of engagement with said tire, and manual means to position said device. 45

2. A traction increasing device for an automobile having a wheel and tire comprising a casing loosely mounted for rotation concentric with the wheel axis, a carrier loosely mounted in said casing, a plurality of spaced outwardly extending 50 plungers having traction plates at their outer ends overlying the tire on said wheel, a friction arm for each plunger movable angularly about the axis of said plunger to engage the tire, a second arm connected to each friction arm, a device movable to a position to engage said second arms and to move said friction arms out of engagement with said tire, a spring to move said device in one direction, and manual means to move said device in the opposite direction. 55

3. A traction increasing device for an automobile having a wheel and tire comprising a casing loosely mounted for rotation concentric with the wheel axis, a carrier loosely mounted in said casing, a plurality of spaced outwardly extending 65 plungers having traction plates at their outer ends overlying the tire on said wheel, a friction arm for each plunger movable angularly about the axis of said plunger to engage the tire, a cam arm connected to each friction arm, a cam plate 70 mounted concentric with the wheel and movable to a position to engage said cam arms and to move said friction arms out of engagement with said tire, and manual means to position said cam plate. 75

4. A traction increasing device for an automobile having a wheel and tire comprising a casing loosely mounted for rotation concentric with the wheel axis, a plurality of spaced outwardly extending plunger mounted in said casing and having traction plates at their outer ends overlying the tire on said wheel, a friction arm for each plunger movable angularly about the axis of said plunger to engage the tire, a cam arm connected to each friction arm, a cam plate mounted concentric with the wheel and movable to a position to engage said cam arms and to move said friction arms out of engagement with said tire, a spring to move said cam plate to said position, and manual means to move said cam plate in the opposite direction.

5. A traction increasing device for an automobile having a wheel and tire comprising a casing loosely mounted for rotation concentric with the wheel axis, a plurality of spaced outwardly extending plunger mounted in said casing and having traction plates at their outer ends overlying the tire on said wheel, a friction arm for each plunger movable angularly about the axis of said plunger to engage the tire, a cam arm connected to each friction arm, a cam plate movable to a position to engage said cam arms and to move said friction arms out of engagement with said tire, and manual means to position said cam plate, said cam plate having cam portions corresponding in number to said plunger and simultaneously actuating all of said cam arms.

6. The combination in a traction increasing device as set forth in claim 5, in which each cam portion has a recess which yieldingly receives one of said cam arms and thereby circumferentially positions said traction plates in predetermined positions and out of contact with the tire-supporting surface.

7. A traction increasing device for an automobile having a wheel and tire comprising a casing loosely mounted for rotation concentric with the wheel axis, a carrier loosely mounted in said casing, a plurality of spaced outwardly extending plunger pivotally connected to said carrier and having traction plates at their outer ends overlying the tire on said wheel, a friction arm for each plunger movable angularly about the axis of said plunger to engage the tire, a cam arm connected to each friction arm, a cam plate movable to a position to engage said cam arms and move said friction arms out of engagement with said tire, and manual means to move said cam plate axially of said wheel, said cam plate having cam portions corresponding in number to said plunger and simultaneously actuating all of said cam arms.

8. A traction increasing device for an automobile having a wheel and tire comprising a casing loosely mounted for rotation concentric with the wheel axis, a swiveled bearing block in said casing, a sleeve angularly movable in said bearing block, a plunger longitudinally movable in said sleeve, a traction plate on said plunger, a tire-engaging friction arm on said sleeve, and manually controlled means to move said friction arm into and out of engagement with the tire.

9. A traction increasing device for an automobile having a wheel and tire comprising a casing loosely mounted for rotation concentric with the wheel axis, a swiveled bearing block in said casing, a sleeve angularly movable in said bearing block, a plunger longitudinally movable in said sleeve, a traction plate on said plunger, a

tire-engaging friction arm on said sleeve, a spring operative to move said sleeve angularly, and manually operative means to resist said spring and to hold said device normally inoperative.

10. A traction increasing device for an automobile having a wheel and tire comprising a casing loosely mounted for rotation concentric with the wheel axis, a carrier angularly movable in said casing, adjustable means to limit angular movement of said carrier in said casing in one direction, a plurality of angularly spaced plunger mounted in said casing and connected to said carrier, and traction plates on said plunger, inward movement of any one traction plate causing angular movement of said carrier relative to said casing and thereby causing simultaneous inward movement of the other plunger.

11. A traction increasing device for an automobile having a wheel and tire comprising a casing loosely mounted for rotation concentric with the wheel axis, a carrier angularly movable in said casing, adjustable means to limit movement of said carrier in one direction, a plurality of angularly spaced plunger mounted in said casing and connected to said carrier, and traction plates on said plunger, inward movement of any one traction plate causing angular movement of said carrier relative to said casing and thereby causing simultaneous inward movement of the other plunger, the connection between each plunger and said carrier being yieldable and permitting further independent movement of any plunger.

12. In a traction increasing device for an automobile having a wheel and tire, a plurality of angularly spaced traction plates, means to hold said plates from rotation with said wheel and in predetermined angular position relative to a horizontal plane, means to release said plates for movement with the associated tire, and means to effect simultaneous movement of all of said plates directly toward or away from said tire in paths of travel parallel to the plane of rotation of said wheel.

13. In a traction increasing device for an automobile having a wheel and tire, a traction plate, means to hold said plate normally out of ground-engaging position and out of contact with the associated tire, a friction member associated with said plate, means to release said member, and means to move said member into frictional engagement with said tire.

14. In a traction increasing device for an automobile having a wheel and tire, a traction plate, means to hold said plate normally out of ground-engaging position and out of contact with the associated tire, a member associated with said friction plate and mounted to swing about an axis approximately radial with respect to said tire, a tire-engaging friction arm at one end of said member, a second arm on said member, and manually positioned means to engage said second arm and to thereby swing said friction arm to inoperative position.

15. In a traction increasing device for an automobile having a wheel and tire, a traction plate, means to hold said plate normally out of ground-engaging position and out of contact with the associated tire, a member associated with said friction plate and mounted to swing about an axis approximately radial with respect to said tire, a tire-engaging friction arm at one end of said member, a second arm on said member, and manually positioned means to engage said second arm and to thereby swing said friction arm to inoperative position, said latter means

being also effective to stop and hold said traction plates out of ground-engaging position.

16. A traction increasing device for an automobile having a wheel and tire, comprising a plurality of angularly spaced traction plates, supports for said plates, means to normally hold each plate yieldingly in outward inoperative position away from the tire, and connections through which all of said plates are moved to operative position against the tread of the tire by engagement of any one of said plates with the surface on which the tire is traveling.

17. A traction increasing device for an automobile having a wheel and tire which comprises a plurality of angularly spaced and substantially radially movable plungers, traction plates on said plungers, friction devices angularly movable about the axes of said plungers to engage said tire, means to normally hold said friction devices in inoperative position, and manual means to release said devices.

18. A traction increasing device for an automobile having a wheel and tire which comprises a casing concentric with said wheel, a plurality of angularly spaced and substantially radially movable plungers mounted in said casing, trac-

tion plates on said plungers, friction devices angularly movable about the axes of said plungers to engage said tire, means to normally hold said friction devices in inoperative position, and manual means to release said devices.

19. A traction increasing device for an automobile having a wheel and tire comprising a support loosely mounted for rotation concentric with the wheel axis, a plurality of spaced outwardly extending members mounted to move toward and from the tire and relative to said support in a direction substantially perpendicular to the wheel axis and having traction plates at their outer ends overlying said tire at all times, means to hold said support and members from rotation with said wheel, and means to cause said members to rotate with said wheel.

20. A traction increasing device for an automobile as set forth in claim 19, in which the means for causing the members to rotate with the wheel is manually controlled but the movement of said traction plates toward the tire tread is automatically effected by engagement of any one of said plates with the surface on which said wheel and tire roll.
